BEVERAGE MIXING DEVICE

Maximilian J. Helmes, Springfield, Mass.

Application April 6, 1934, Serial No. 719,325

2 Claims. (Cl. 259—91)

This invention relates to mechanical mixing devices particularly adapted for the blending or mixing of beverages with vehement agitation as is desirable in the mixing of solid, dissolvable substances such as ices in alcoholic drinks or the mixing of malted milk and flavoring powders in milk shakes and like beverages.

An important feature of my improved device consists in the provision of resilient or spring supporting means for the container or containers adapted upon displacement from normal or rest position and release to effect a rapid up and down movement of the container under the resiling or rebound action of the springs and the provision of a cam or like acting means for intermittently displacing the supporting means to energize the springs for continued repetition of the rebounding or agitating movement of the containers thus to produce a vehement shaking of the containers and contents.

A further feature of the present improvements consists of means for varying the rapidity of the action of the cam, means for controlling the degree of agitating of the liquids as may be desired.

The foregoing and other important features and advantages of my present invention will be more fully understood by reference to the accompanying drawings wherein like reference characters are applied to the corresponding parts in the several views.

In the drawings:

Fig. 1 is a view in side elevation of my improved agitating device with the containers in assembled relation thereto.

Fig. 2 is a view similar with portions shown in central vertical section.

Fig. 3 is a central vertical sectional view, taken at right angles to that of Fig. 2.

Fig. 4 is a horizontal sectional view, taken on line 4—4 of Fig. 2.

Fig. 5 is a detailed vertical sectional view of the upper adjustable holding device.

Fig. 6 is a central vertical sectional view showing a desirable modification for manual operation.

Fig. 7 is a view in side elevation taken at right angles to Fig. 6.

Fig. 8 is a horizontal sectional view on line 8—8 of Fig. 7 and

Fig. 9 is a detailed view in elevation of the cam mechanism.

In the approved embodiment of the features of my invention as shown in Figs. 1 to 9 the device comprises a unitary standard or base struc-

ture in which the drive or operating mechanism is located, a support resiliently mounted to hold the lower container and carrying an adjustable folder or fastener for the upper container member. The standard or base is shown at 1 and has integral therewith oppositely positioned bearing flanges 2 and 3 provided with a lower bearing 4 for the shaft 5 of an electric drive motor M and with upper bearings 6 and 7 for a cam shaft 8 coupled to be driven by the motor through the meshing pinions 9 and 10 mounted upon the shafts 5 and 8 respectively. Central of the shaft 8 it is formed with a cam 12. Symmetrically disposed about the central vertical axis of the device, a standard is provided with four fixed vertical guide sleeves 14 to receive a telescoping arrangement co-acting guide studs 15, mounted upon the under side of a movable support or carrier 16 for the liquid container. The carrier 16 is resiliently supported upon coil springs 18, positioned to surround the sleeves 14 and studs 15 and connected at their upper ends to the carrier 16 and at their lower ends to the base so as to normally support the carrier in a suspended or floating relation determined by the position of rest of the spring supports. Upon a depending bracket 20 on the under side of the carrier 16 there is provided a suitably journaled roller 21 in position to be engaged by the cam element 12 referred to. The carrier is further provided with an upwardly extending annular flange member 22 having fitted to an internal groove therein a rubber gasket 23 for the reception of the lower container 24 for the liquid with which cooperates the inverted upper container 25 received partially within the lower container and which is held in position by an adjustable holding element 27 provided with a rubber cushion 28 engaging the end wall or bottom of the upper container as shown and having a bracket 30 slidably fitted upon a rack guide member 31 formed integral with or affixed to the carrier member 16 and flange 22 thereof. The right member 31 is, as shown, provided with the spaced teeth 32 engaged by a rockable detent 33 pivoted at 34 in the bracket 30 and normally held in engaging position by spring 35. Suitable housing 36 is provided upon the standard to encase the operating motor and the carrier member 16 has affixed thereto and cylindrical covered plate 38 having telescoping relation to the central portion of the standard to enclose the operating parts as shown.

In the operation of my improved device, as will be readily understood, the receptacles 24

and 25 in their inverted nesting relation, will form a close container for the liquid and other ingredients to be dissolved therein by agitation, the containers being placed upon the supporting member or carrier 16 in the position as shown where they are securely clamped by means of the upperholder 27 adjustable upon the rock 32. Upon then energizing the motor M by means of the customary rheostat control R therefor, the cam 5 shaft 8 will be rotated and by its engagement with the roller 21 will intermittently impart a lifting movement to the container support 16, thereby energizing or elongating the springs 18 whereby, upon being released upon a further forward motion of the cam they will act with full resiliency to affect the reciprocation of the carrier 16 with a relatively violent or vehement rebound action. The form of the cam, as will be noted, is such as to allow of the free, resilient action of the springs immediately after the roller engagement and the adjustment of the rheostat covering the motor speed will determine the degree of agitation as may be desired.

In Figs. 6 to 9 I have shown a desirable, modified construction of my improved mixing device which, as shown, comprises an angular supporting base member 40, having an upright bearing bracket 41, having a cam shaft bearing 42 to receive the shaft 43, having on its innermost end an actuating cam 44 and on its outer extremity an operating lever 45. The standard is likewise provided with upper and lower guide studs 46 and 47, slidably fitted within vertical guideways or grooves 48 and 49 of a vertical, movable carrier frame or container supporting member 50, integrally formed at its lower portion with an annulus 52 carrying the cushioning ring 53 for the reception of the lower receptacle or container 55. An upper extension of the carrier 50 is, as shown, formed as a rack 56 upon which is slidably fitted a bracket 58 of the upper holder 59, retained in its position by the spring latch detent 60 in similar arrangement to that disclosed in connection with the structure first described and operating to hold the upper container or receptacle member 62 in assembled position.

The carrier member 50 at its lower portion is provided with a stud 63 to which is adjustably secured a coil spring 64 connected at its upper end to the base member as shown.

For actuating the carrier member 2 to effect a reciprocating movement thereof under the free action of the spring, the carrier member is formed with an enlarged opening 66 for the reception

of the cam 44 and the latter, as best shown in Fig. 9 is keyed upon the shaft 43 with a circumferentially enlarged keyway 68 which, in conjunction with the formation of the cam as shown, will operate to effect displacement of the carrier from normal rest position and a quick acting release thereof upon the cam passing center as will be readily understood.

Accordingly in operation upon rotation of the cam by means of the lever 45 will intermittently energize the spring 64 by displacement of the carrier from normal rest position with quick acting release thereof, allowing the spring to act freely to impart a relatively violent reciprocating motion to the containers in the manner well understood.

While I have shown apparent embodiments of the features of my invention, it will be understood that various modifications may be made within, without departing from the invention as defined in the appended claims.

Having described my invention, I claim:

1. A mixing device of the character described, comprising a base member having a vertical bracket, guide studs on the bracket, a container carrier member formed with guideway slots fitted to the studs, an operating shaft journaled in the bracket, an actuating cam rotatively keyed on the shaft with an elongated slot allowing of limited free movement and positioned to engage the carrier, spring supporting means for the carrier connected to the carrier and bracket respectively, a container holder on the carrier adapted to receive a lower receptacle, a vertical rack on the carrier, an upper holder adjustably fitted to the rack for engagement with an upper receptacle and a lever on the operating shaft for manual rotation thereof.

2. A mixing device of the character described, comprising a base member having a vertical bracket, guide studs on the bracket, a container carrier member formed with guideway slots fitted to the studs, an operating shaft journaled in the bracket, an actuating cam rotatively keyed on the shaft with an elongated slot allowing of limited free movement and positioned to engage the carrier, spring supporting means for the carrier connected to the carrier and bracket respectively, a container holder on the carrier adapted to receive a lower receptacle, a vertical rack on the carrier, an upper holder adjustably fitted to the rack for engagement with an upper receptacle and means for rotating the operating shaft.

MAXIMILIAN J. HELMES.
